PLIER-TYPE SLIDABLE JAW WRENCH

Arthur Daugherty, Sardis, British Columbia, Canada
Application December 15, 1954, Serial No. 475,355

2 Claims. (Cl. 81—85)

This invention relates to a tool, and more particularly to a wrench.

The object of the invention is to provide a wrench which includes a manually operable mechanism for controlling the size or maximum opening of the jaws, there being a spring means for automatically releasing the jaws when pressure on the wrench is released.

Another object of the invention is to provide an all purpose wrench which includes a spring for holding the jaws open when pressure is released and wherein a high mechanical advantage is developed, the wrench being constructed so that the teeth of both jaws ride clear of the pipe or other workpiece upon or on the return stroke of the wrench.

A further object of the invention is to provide a wrench which is extremely simple and inexpensive to manufacture.

Other objects and advantages will be apparent during the course of the following description.

In the accompanying drawings, forming a part of this application, and in which like numerals are used to designate like parts throughout the same:

Figure 1 is a side elevational view of the wrench of the present invention, with parts broken away and in section.

Figure 2 is a fragmentary side elevational view of the wrench, showing certain details of the construction in section.

Figure 3 is a sectional view taken on the line 3—3 of Figure 2.

Figure 4 is a sectional view taken on the line 4—4 of Figure 2.

Figure 5 is a sectional view taken on the line 5—5 of Figure 2.

Figure 6 is a sectional view taken on the line 6—6 of Figure 2.

Figure 7 is an elevational view of the adjustment rod, with parts broken away and in section.

Referring in detail to the drawings, the numeral 10 designates a body member which can be made of any suitable material, and the body member 10 includes a pair of spaced parallel side walls 11 which are interconnected by means of an arcuate web 12. Interposed between the pair of side walls 11 is an elongated rod 14 of circular cross section, and the rod 14 includes an exteriorly threaded portion 15 that has a knurled stop nut 16 arranged in threaded engagement therewith. Formed integral with one end of the rod 14 or secured thereto is a lip 17 which is provided with a shoulder 18 for a purpose to be later described. The lip 17 is provided with an aperture 19 through which extends a pivot pin or bolt and nut assembly 20.

Secured to the body member 10 is a stationary jaw 21, and the jaw 21 is provided with a plurality of teeth 22. The jaw 21 may be secured between the pair of side walls 11 by suitable securing elements such as rivets 23.

The wrench of the present invention further includes a movable jaw which is indicated generally by the numeral 24, and the jaw 24 includes a straight section 25 which is mounted for movement towards and away from the

stationary jaw 21. The straight section 25 is provided with a plurality of teeth 26 which are adapted to engage a workpiece such as a pipe being handled, and extending from the straight section 25 and secured thereto or formed integral therewith is a shank 27. The shank 27 includes a first portion 28 and a second portion 29 which is arranged angularly with respect to the first portion 28. Extending from the second portion 29 is a third portion 30. There is further provided a handle which is indicated generally by the numeral 31, and the handle 31 includes a pair of spaced parallel side members 32 which are interconnected by a curved portion 33. A spring member 34 has one end secured to the handle 31 by means of a bolt and nut assembly 35, Figure 1, while the other end of the spring member 34 engages or abuts the third portion 30 of the shank 27 of the movable jaw 24.

The side walls 11 of the body member 10 are provided with a first pair of opposed slots 36 through which the pivot pin 20 extends, and the side members 32 of the handle 31 are provided with opposed circular apertures 37 through which the bolt or pin 20 also extends. The side walls 11 are further provided with a second pair of opposed spaced parallel slots 38 and a bolt and nut assembly or pin 39 also extends through the pair of slots 38. The pin 39 extends through circular apertures 40 in the side members 32 of the handle 31, and the bolt 39 also extends through an opening 41 in the second portion 29 of the shank 27.

From the foregoing it is apparent that there has been provided a wrench and in use the article to be gripped such as the pipe extends through the space between the teeth 26 and the teeth 22. Then, the handle 31 is manually pressed towards the body member 10 and this causes the teeth 26 to move towards the teeth 22. This occurs because when the handle 31 is moved towards the body member 10, the bolt 39 will be pulled rearwardly in the slots 38 to thereby cause movement of the jaw 24 towards the jaw 21. Thus, with the teeth 26 and 22 frictionally engaging a portion of a pipe or other workpiece, the pipe can be rotated, or otherwise moved or manipulated. On the return stroke of the wrench, it is only necessary to manually release pressure on the handle 31 whereby the spring member 34 will move the handle 31 from the broken line position of Figure 1 to the solid line position of Figure 1 so that the jaw 24 will move from the dotted line position of Figure 1 to the solid line position whereby the teeth will not engage the pipe on the return stroke so that the wrench can be quickly and easily made ready for the next work stroke. By adjusting the nut 16 on the threaded portion 15 of the rod 14, the amount or distance that the jaw 24 is permitted to open or travel can be regulated. Thus, it will be seen that the nut 16 abuts the end of the body member 10 so as to limit further inward movement of the rod 14. Further, a portion of the shank 27 abuts the shoulder 18 on the lip 17 so that opening movement of the jaw 24 is limited by the position or point at which the inclined or second portion 29 contacts the shoulder 18. Thus, by varying the position of the nut 16 on the threaded portion 15, the permissible opening movement of the jaw 24 can be controlled as desired. The various bolts or pins can be provided with bushings so as to insure that the moving parts will move more smoothly. The size of the wrench can be varied as desired. The handle 31 and body member 10 can be stamped out of sheet metal and the jaws can be made of steel. The rod 14 controls the maximum opening of the jaws and the spring 34 holds the handle 31 open when pressure thereon is released. The wrench can be used for all work that can be done by means of a pipe wrench, crescent wrench, or other type of adjustable wrench, and the wrench of the present invention is economical to make, light in weight and easy to use. An important advantage of the present invention is that when a pipe is fully inserted between the jaws so as to ride against the

3

neck of the outer jaw 24, the teeth 26 and 22 of both jaws ride clear of the pipe on the return stroke. The present invention is a general purpose wrench which can be used as a pipe wrench and operates somewhat like a pair of pliers which close or open by means of the handle 31.

I claim:

1. In a wrench, a body member including a pair of spaced parallel side walls, an arcuate web interconnecting said side walls, there being a first and second slot in each of said side walls, the pairs of slots being arranged in opposed relation with respect to each other, a rod extending between said side walls and including an exteriorly threaded end portion, a securing element arranged in engagement with said threaded end portion, a lip arranged on the inner end of said rod and provided with a shoulder thereon, said lip having an aperture registering with the first slots in said side walls, a pivot pin extending through the aperture in said lip and through said first slots, a stationary jaw secured between said pair of side walls and provided with a plurality of teeth thereon, a movable jaw including a straight section having teeth thereon mounted for movement towards and away from said stationary jaw, a shank extending from the straight section of said movable jaw and including a first portion and a second portion arranged angularly with respect to each other, a third portion extending from said second portion, a handle including a pair of spaced parallel side members interconnected by an arcuate portion, a securing element extending between the side members of said handle and through the second slots in said body member and through the second portion of said shank, said pivot pin extending between the side members of said handle, and a spring member having one end secured to said handle and its other end engaging the shank of said movable jaw.

2. In a wrench, a body member including a pair of side

walls, a web interconnecting said side walls, there being a first and second slot in each of said side walls, the pairs of slots being arranged in opposed relation with respect to each other, a rod extending between said side walls and including an end portion, a securing element arranged in engagement with said end portion, a lip arranged on said rod and provided with a shoulder thereon, said lip having an aperture registering with the first slots in said side walls, a pivot pin extending through the aperture in said lip and through said first slots, a stationary jaw secured between said pair of side walls and provided with a plurality of teeth thereon, a movable jaw including a straight section having teeth thereon mounted for movement towards and away from said stationary jaw, a shank extending from the straight section of said movable jaw and including a first portion and a second portion, a third portion extending from said second portion, a handle including a pair of side members interconnected by an arcuate portion, a securing element extending between the side members of said handle and through the second slots in said body member and through the second portion of said shank, said pivot pin extending between the side members of said handle, and a spring member having one end secured to said handle and its other end engaging the shank of said movable jaw.
